(57) **CLAIM**

The ornamental design for a laparoscopic bipolar electro-surgical device, as shown and described.

DESCRIPTION

FIG. 1 is a top perspective view of a laparoscopic bipolar electro-surgical device;
FIG. 2 is a top plan view thereof;
FIG. 3 is a right side elevation view thereof;
FIG. 4 is a bottom plan view thereof;
FIG. 5 is a left side elevation view thereof;
FIG. 6 is a front elevation view thereof; and,
FIG. 7 is a rear elevation view thereof.
